UNITED STATES PATENT OFFICE.

JOHN HETTRICH, OF GRAND ISLAND, NEBRASKA, ASSIGNOR OF ONE-HALF TO GILBERT VANSKIKE, OF GRAND ISLAND, NEBRASKA.

CRATE.

No. 889,849.

Specification of Letters Patent.

Patented June 2, 1908.

Application filed August 9, 1907. Serial No. 387,795.

To all whom it may concern:

Be it known that I, JOHN HETTRICH, a citizen of the United States, and resident of Grand Island, in the county of Hall and State of Nebraska, have invented an Improvement in Crates, of which the following is a specification.

My invention is an improvement in crates, and consists in certain novel constructions and combinations of parts hereinafter described and claimed.

Referring to the drawings forming a part hereof, Figure 1 is a side view of the complete crate. Fig. 2 is a longitudinal section. Fig. 3 is a horizontal section on line 3—3 of Fig. 1. Fig. 4 is a view of the sheet of fabric material forming the bag. Fig. 5 is a detail of the fastening device for the bag; and Fig. 6 is an end view of the crate folded.

20 In the practical application of my invention, I provide a crate comprising a frame A, a bag B, and a fastening device C for connecting the bag with the frame.

The frame A is composed of a plurality of 25 hoops a, three in the present instance, and each of the hoops is composed of three sections, a', a², a³, the sections a', a³, being hinged to the ends of the section a² as at a⁴, and the free ends of the sections a', a², over- 30 lap, the section a³ being provided with a pin a⁵ traversing an opening in the end of the section a', the parts being secured together by a cotter pin a⁶ traversing an opening in the pin a⁵.

35 A plurality of staves a⁷ connect the corresponding sections of the respective hoops together, the staves being arranged at spaced intervals, and each of the sections is lined with a lining of tin a⁸, the tin being provided 40 with numerous perforations a⁹ for permitting a free circulation of air through the frame.

The bag B comprises a sheet of fabric material b, having its top and bottom edges hemmed as at b', and the sheet is provided 45 with spaced series of parallel slots b² for a purpose to be presently described, and when arranged within the frame, the ends of the sheet are brought together and tied as at b³, with the free edges of the sheet b⁴ overlapping each other.

50 The bag is connected to the frame by means of fasteners C, comprising an arc shaped body portion c, and a threaded stem c', the body portion being of a length equal 55 to the length of the slots, and adapted to be

inserted therethrough and turned as shown at c³ in Fig. 2, the threaded stem projecting through an opening in a stave, and having thereon a nut c², whereby the arc shaped body portion may be drawn toward the 60 stave to compress the sides of the slot between the body portion of the fastener and the stave.

As shown in the drawing, two annular series of the fasteners are arranged between 65 each hoop, but it is evident that more or less may be used as desired.

My improved crate is especially adapted for the reception of fruits and vegetables, such as bananas, cucumbers, etc., and when 70 empty, the crate may be folded into the shape shown in Fig. 6, to reduce the bulk in returning the crate.

When the bag B becomes dirty, it may be removed from the frame and washed, or 75 replaced by another bag. The framework is ordinarily formed of pressed steel, and when set up as shown in Figs. 1 and 3, is strong enough to resist all ordinary rough usage, and to preserve its contents from 80 injury.

It will be obvious from the description, that my improved crate comprises a collapsible frame lined with a sheet of fabric material, the ends of the sheet projecting 85 beyond the ends of the crate, and adapted to be tied to form an inclosure, the free edges of the sheet overlapping, thus forming a bag.

While I have shown and described the fabric material as extending from end to 90 end of the crate, it is obvious that the central portion of said sheet might be omitted, it only being necessary to have enough fabric material to form the ends for tying, the crate consisting of a collapsible frame 95 having ends of fabric material capable of being tied to form an inclosure.

I claim:

1. A crate of the class described, comprising a framework, composed of a plurality of 100 hoops, each made in three sections, two of the sections being hinged to the ends of the other section, the free ends of said first named sections overlapping, and one being provided with a pin and the other with an 105 opening through which the pin passes, said pin being provided with an opening, and a cotter pin traversing the opening, staves connecting the corresponding sections of the 110 hoops, said staves being spaced apart from

- each other, a bag comprising a sheet of fabric material provided with a plurality of rows of spaced slots, and a plurality of fastening devices comprising an arc shaped body portion and a threaded stem, the body portion being of a length corresponding to the length of a slot of the bag, and adapted to be introduced therethrough and turned at right angles to the length of the slot, the threaded stem 5 traversing an opening in the stave, and a nut threaded on the stem whereby to draw the body portion of the device toward the stave to clamp the fabric material between said body portion and the stave.
- 10 15 2. A crate of the class described, comprising a frame composed of a plurality of hoops, each of said hoops comprising a plurality of hinged sections, staves connecting the corresponding sections of the respective hoops,
- 20 25 30 35 40 45 50 55 60 65 70 75 80 85 90 95 100 105 110 115 120 125 130
- a sheet of fabric material provided with a plurality of rows of spaced slots, and a plurality of fastening devices for securing the sheet to the inner face of the frame, said fastening devices each comprising an arc shaped body portion and a threaded stem, the body portion being of a length corresponding to the length of a slot of the bag, and adapted to be introduced therethrough and turned at right angles to the length of the slot, the threaded stem traversing an opening in the stave, and a nut threaded on the stem whereby to draw the body portion of the device toward the stave to clamp the fabric material between said body portion and the stave.
3. A crate of the class described, comprising a frame composed of a plurality of hoops, staves connecting the hoops with each other, said staves being spaced apart from each other, a sheet of fabric material arranged within the crate with its edges overlapping, the ends of the sheet being adapted to be brought together and tied to form an enclosure, said sheet being provided with a plurality of rows of parallel slots, and means for connecting the sheet with the crate, said means comprising a plurality of fastening devices, each comprising an arc shaped body of a length corresponding to a slot of the sheet, and a threaded stem, the body being adapted to be introduced through a slot and turned at right angles thereto, the threaded stem traversing an opening in the stave, and a nut on the stem, whereby to draw said body portion toward the stave to clamp the bag between the stave and the body portion.
4. A crate of the class described, comprising a cylindrical collapsible frame, a sheet of fabric material arranged within the frame, said sheet having its free edges overlapping, the ends of the sheet being adapted to be brought together, and tied to form an enclosure, said sheet being provided with a plurality of parallel slots, and means for securing the sheet to the frame, comprising a

plurality of fastening devices, each comprising an arc shaped body of a length corresponding to a slot of the sheet, and a threaded stem, the body being adapted to be introduced through a slot and turned at right angles thereto, the threaded stem traversing an opening in a stave, and a nut on the stem, whereby to draw said body portion toward the stave to clamp the stave between the stave and the body portion.

5. A crate of the class described, comprising a cylindrical frame, a sheet of fabric material arranged within the frame, said sheet having its free edges overlapping, the ends of the sheet being adapted to be brought together and tied to form an enclosure, said sheet being provided with a plurality of slots, and means for securing the sheet to the frame, comprising a plurality of fastening devices, each consisting of an arc shaped body of a length corresponding to a slot, and a stem, the body being adapted to be introduced through a slot and turned at right angles thereto, the stem traversing an opening in a stave, and means engaging the stem to draw said body portion toward the stave, to clamp the sheet between the stave and the body portion of the fastener.

6. A crate of the class described, comprising a frame, a sheet of fabric material arranged within the frame, said sheet having its free edges overlapping, the ends thereof being adapted to be brought together and tied to form an enclosure, said sheet being provided with a plurality of slots, and means for securing the sheet to the frame, said means comprising a body portion adapted to be introduced through a slot and turned transversely thereof, and means in connection with the body portion and engaging a stave for drawing said body portion against the stave, whereby to clamp the sheet between the stave and the body portion.

7. A crate of the class described, comprising a framework composed of a plurality of hoops, each made in three sections, two of the sections being hinged to the ends of the other section, the free ends of said first named sections overlapping, means for securing said free ends together, staves connecting the corresponding sections of the hoops, said staves being spaced apart from each other, a perforated metallic lining for each of the sections, and a sheet of fabric material detachably connected to the staves within the frame, the ends of the sheet projecting beyond the ends of the frame and adapted to be tied to form an enclosure.

8. A crate of the class described, comprising a frame composed of a plurality of hoops, each of said hoops comprising a plurality of hinged sections, staves connecting the corresponding sections of the respective hoops, a metallic perforated lining connecting the respective sections of the hoops and the staves

connected therewith, a sheet of fabric material detachably connected with the staves within the frame, the ends of the sheet projecting beyond the ends of the frame and

5 adapted to be tied to form an inclosure.

9. A crate of the class described, comprising a collapsible frame, a metallic perforated lining for the frame, and a sheet of fabric material detachably connected to the frame

within the same, said fabric material projecting beyond the ends of the frame, whereby to permit tying thereof to form an inclosure.

JOHN HETTRICH.
